H. SKREBERG,
PROTECTOR FOR RADIATORS,
APPLICATION FILED NOV. 8, 1915.
1,196,403.

Patented Aug. 29, 1916.

UNITED STATES PATENT OFFICE.

HANS SKREBERG, OF BIG BEND TOWNSHIP, CHIPPEWA COUNTY, MINNESOTA.

PROTECTOR FOR RADIATORS.

1,196,403.

Specification of Letters Patent. Patented Aug. 29, 1916.

Application filed November 8, 1915. Serial No. 60,352.

To all whom it may concern:
Be it known that I, HANS SKREBERG, a citizen of the United States, residing at Big Bend township, in the county of Chippewa, 5 State of Minnesota, have invented a new and useful Protector for Radiators; and I do hereby declare the following to be a full, clear, and exact description of the invention, such as will enable others skilled in 10 the art to which it appertains to make and use the same.

This invention relates to an improved protector for radiators of automobiles generally, and particularly adapted for radiators of the "Ford" type of automobiles. 15 Through experience it has been found that the radiator starts freezing at the forward bottom portion thereof. This is particularly evidenced on the "Ford" type of automobile.

Therefore an object of the present invention is to provide an improved protector for the lower forward edge of the bottom portion of the radiator, consisting of plate 25 having a part overlying the lower forward face of the radiator provided with attaching means connected to the face of the radiator, and provided with a bent portion at its lower edge extending under the radiator.

30 One of the features of the invention is the provision of improved means for preventing the protector from marring or scarring the finish of the radiator.

Another object of the invention is to provide the protector plate with means to accommodate the drain cock at the lower part 35 of the radiator.

Another feature of the invention is to provide means for accommodating the carbureter priming rod.

In practical fields the details of construction may necessitate alterations, falling within the scope of what is claimed.

The invention comprises further features 45 and combination of parts, as hereinafter set forth, shown in the drawings and claimed.

In the drawings: Figure 1 is a view in perspective of a radiator, particularly of the style or construction belonging to the 50 "Ford" type or construction of machine, illustrating the improved protector as applied. Fig. 2 is an enlarged detail perspective view of the protector, showing the front face thereof. Fig. 3 is an enlarged 55 detail perspective view of the protector, showing the reversed face to that shown in

Fig. 2. Fig. 4 is a view partly in section and parts broken away, illustrating the manner in which the protector plate is secured in position, illustrating the felt. Fig. 69 65 5 is a view partly in section and partly in plan showing the felt washers, instead of showing the felt extending in one piece as illustrated in Fig. 3. Fig. 6 is a detail view of one of the fasteners for securing the protector in position. Fig. 7 is a detail perspective view of one of the felt washers.

Referring more especially to the drawings, 1 designates the usual form of radiator, as used upon the "Ford" type of machine, illustrating the carbureter priming rod substantially at the lower left hand corner thereof, which rod is designated by the numeral 2. To protect and keep the lower forward portion of the radiator from freezing to a considerable extent an improved protector 3 is provided, which consists of a sheet metal plate 4, which is bent angular in cross section, at 5, so as to provide the vertically extending flange 6, and a horizontal flange 7. The vertical flange 6 extends adjacent the front face of the radiator, while the horizontal flange 7 extends under the lower face of the radiator. This horizontal flange 7 is of just the necessary 85 length, to extend from *a* to *b* and fit between the supporting frame 8, at 9 and 10 of said frame. This horizontal frame 7 is also above the upper face of the bearing 11 of the crank shaft 12 of the machine, 90 so as to be partially supported by said bearing. However, the vertical flange 6 is longer than the horizontal flange, so as to extend fully to the opposite side edge corners 13 of the radiator. The horizontal 95 flange 7 toward the right hand side is provided with a cutaway portion or slit 14, and the metal adjacent the opposite sides of the cutaway portion or slit is bulged or depressed, or otherwise formed, as shown to 100 conform to that portion of the drain cock 15 where it projects from the under portion of the radiator, in order to provide a neat fit and appearance. The vertical flange 6 to the left is provided with a slot or opening 16 to receive and accommodate the carbureter priming rod 2. The upper edge portion of the flange 6 is bent upon itself as shown at 18 and against the inner face of said flange, and the opposite ends of this 110 bent portion 19 engage the shoulders 20 of the brass frame 21 of the radiator, thereby

assisting in preventing endwise movement of the protector. Arranged between the protector plate and the radiator, and conforming to the angular contour of the plate 5 is a strip of felt 22, thereby protecting the radiator against scarring or marring of the finish. The upper edge of this felt abuts against the lower edge of the bent over portion 19 of the vertical flange 6 as shown 10 at 23.

The vertical flange 6 near the right and left ends thereof and a little below where the upper part of the flange 6 is bent at 18, is provided with slits or slots 24, for the reception of the fastening devices 25. Each 15 of the fastening devices consists of a strip of sheet metal bent to form a T-shaped head 26 engaging the outer face of the protector, whereas the arms 27 of the fastening devices penetrate through the cells of the radiator, and have their extremities bent laterally in opposite directions, as shown at 28, thereby securely fastening the protector firmly or rigidly in position, and against 25 straddling, or otherwise displacing incident to the vibration of the machine when under way. In Figs. 5 and 7, it is to be noted that instead of the felt extending the entire width 30 of the radiator, there are provided felt washers 29, which conform to the angular contour of the protector plate, and are located just where the fastening devices are employed to secure the protector in position. However, when employing either the one 35 long piece of felt or the felt washers, the fastening devices penetrate the same.

The invention having been set forth, what is claimed as new and useful is:—

1. A radiator protector consisting of a 40 sheet metal plate angular in cross section, to form a vertical flange engaging the lower forward face of the radiator, and a

horizontal flange engaging the under face of the radiator, fastening clips for securing the vertical flange to the front face of the 45 radiator, and a strip of felt conforming to the angular contour of the plate, between the plate and the radiator, the upper portion of the vertical flange being bent upon itself and against the inner face of said flange, the 50 lower edge of said bent portion abutting the upper edge of the felt, the opposite ends of the bent portion abutting and fitting between the side vertical shoulders of the brass framing of the radiator.

2. A radiator protector consisting of a sheet metal plate angular in cross section, to form a vertical flange engaging the lower forward face of the radiator, and a horizontal flange engaging the under face of the 60 radiator, fastening clips for securing the vertical flange to the front face of the radiator, and a strip of felt conforming to the angular contour of the plate, between the plate and the radiator, the upper portion of the vertical flange being bent upon itself and against the inner face of said flange, the 65 lower edge of said bent portion abutting the upper edge of the felt, the opposite ends of the bent portion abutting and fitting between the side vertical shoulders of the brass framing of the radiator, one end of the vertical flange having a slot for the reception and accommodation of the carbureter priming rod, said horizontal flange at one end having a cutaway portion for the accommodation of the drain cock of the radiator.

In testimony whereof I have signed my name to this specification in the presence of two subscribing witnesses.

HANS SKREBERG.
